CHARLES AUGUSTUS BUTLER, OF OKMULGEE, OKLAHOMA.

DEEP-WELL-DRILLING TOOL.

1,116,794.

Specification of Letters Patent. Patented Nov. 10, 1914.

Application filed December 3, 1913. Serial No. 804,394.

To all whom it may concern:

Be it known that I, CHARLES A. BUTLER, a citizen of the United States, and a resident of Okmulgee, in the county of Okmulgee and State of Oklahoma, have invented a new and Improved Deep-Well-Drilling Tool, of which the following is a full, clear, and exact description.

This invention relates to deep well drilling or boring apparatus, and has particular reference to a drilling device for operating rapidly and successively through earth or rock having varying degrees of hardness.

Among the objects of the invention is to so equip a rock drill as to provide for a proper circulation of the fluids surrounding the drill bit so as to prevent the gumming up and sluggish operation of such tool while operating through soft or sticky material. The foregoing and other objects of the invention will hereinafter be more fully described and claimed and illustrated in the drawings forming a part of this specification in which like characters of reference indicate corresponding parts in both the views, and in which—

Figure 1 is a vertical section of a portion of the bore of a well being drilled and with the drilling tools at the bottom, heavy dash lines indicating thick or sticky mud and light dash lines indicating thinner mud or fluid; and Fig. 2 is a vertical sectional view of the valve mechanism and structure of the connections between the drill stem and drill bit.

The several parts of the device may be made of any suitable materials, and the relative sizes and proportions, as well as the general design of the mechanism, may be varied to a considerable extent without departing from the spirit of the invention hereinafter more fully set forth and specifically claimed.

By way of further explanation of the necessity for this improvement, it may be observed that in drilling wells with what is known as "cable tools", the method employed is to keep the drilling tools surrounded with sufficient water to mix up the crushed rock as it is cut loose and keep the sediment thin enough to allow the tools to drop freely through it. The ordinary

amount of water used will keep the sediment thin while drilling about twelve feet of hole in or through hard rock, such as sandstone or limestone, but in soft rock, such as slate, shale or redrock, with the ordinary tools now used, it is impossible to drill more than six feet with the same amount of water, for the fluid around the tools becomes very thick at the bottom, as indicated by the heavy dash lines as above referred to, preventing the tools from dropping freely, the fluid remaining thin, however, farther up in the well hole. As soon as the fluid becomes thick at the bottom of the hole, it is necessary to withdraw the tools from the hole and bail out the fluid, and then run in fresh water and repeat the drilling operation. If, however, the water can be made to mix thoroughly with the rock as it is cut loose, it is possible and practical to drill as much hole at each run in soft rock as it is in hard, thus doubling the amount of hole per run and saving a great deal of time.

One of the primary objects of the invention, therefore, is to cause the thin fluid to circulate downwardly through a considerable portion of the drill stem and through the drilling bit whereby the circulation will keep the stone cuttings or sediment well mixed or stirred up so that the drill will drop freely therethrough for a considerable length of time before requiring the drilling tools to be removed for bailing out the hole. In carrying out this object in a preferred manner, the stem 10 is chambered or bored out centrally at 11 from its lower end upward approximately throughout one half of its length, and the upper end of the bore 11 is made to communicate with the side of the stem by an upwardly inclined hole 12. It will be understood that sufficient water is delivered into the well hole to insure the hole 12 being covered and providing that a column of water or thin mud or mixture will be maintained in the vertical bore 11.

The lower end 13 of the stem constitutes an internally chambered socket for the accommodation of valve mechanism and providing a means for connecting thereto the drill bit shank 14. Said chamber 15 is provided with a screw thread 16 which receives

2
the threaded hub 17 of the aforesaid shank. The chamber 15 is extended upwardly from the aforesaid hub providing a seat for valve mechanism including a pair of heavy rubber gaskets 18 and 19 between which are fitted a pair of plates 20 and 21, said plates being held in definite position by said gaskets, the gaskets filling the recess or chamber sufficiently tightly to maintain the 5 valve mechanism in position even though the drill bit be removed from the shank socket. The plate 20 includes an annular valve seat 20' against which the valve 22 is seated upwardly and there maintained normally by means of a spring 23 seated at its 10 lower end upon a bridge 24 carried by the lower plate 21. The stem bore 11 leads to said valve through the upper gasket 18.

The drill bit 25 is so constructed that its 20 shank 14 is provided with a substantially central bore 26 leading from the valve mechanism through the lower gasket 19. Said bore 26, however, at its lower end communicates with a pipe or tube 27 leading downwardly along one face of the bit 25 and has its lower end open and adapted to discharge close to the cutting edge 25' of the bit. Said tube 27 is held in place at its lower end closely adjacent the bit by means of a 25 keeper 28.

Having thus set forth a description of the mechanism, the manner of operation may be briefly described as follows: A certain quantity of clear water being introduced into the 30 hole being drilled, the drilling tool will be operated in the usual manner and allowed to drop to the bottom of the hole acting upon the rock at such point. Water or thin fluid mixture will enter the hole 12 and fill the bore 11. The percussion due to the striking 40 of the drill bit against the bottom of the hole will cause a portion of the column of water filling the bore 11 to pass downwardly past the valve, filling the bore 26 and space below the valve mechanism, more water entering the bore 11 to take its place from the 45 outside of the drill stem. When the drilling tool is lifted for a subsequent drop, the valve will open by suction, allowing the water to pass freely downwardly from the bore 11, whereby upon the subsequent down 50 stroke the water delivered through the bore 26 and tube 27 will be forced upwardly around the drill bit insuring complete circulation. In addition to the spring 23 55 serving to hold the valve normally closed, it acts as a cushion for the valve at the time of the impact of the drill bit. It will be also noted that the gaskets 18 and 19 fit snugly 60 against the upper end of the hub 17 and prevent sand or sediment from getting into the threads of the socket and said hub.

Having thus described my invention, I claim as new and desire to secure by Letters 65 Patent:—

1. In deep well drilling apparatus, the combination of a drill stem having a vertical bore extending therethrough from the lower end thereof and a lateral hole leading through the side of the stem and communicating with the upper end of said bore, said stem furthermore being provided with a socket at its lower end providing a valve seat, a drill bit secured in said socket for operation through said stem, said drill bit being provided with a passageway for water or fluid leading from said chamber down adjacent the cutting edge of the bit, and valve mechanism mounted in the upper end of said chamber and serving to insure the circulation of water or fluid downwardly through said bore and passageway, said mechanism comprising a pair of solid rubber gaskets fitted in said socket, a pair of metallic plates located between said gaskets 80 and held in position thereby, one of said plates constituting a valve seat and the other of the plates having a bridge extending across it spaced from said valve seat, a valve mounted between said bridge and the 85 valve seat, and a spring bearing at one end against the bridge and at the other end against the valve.

2. In deep well drilling apparatus, the combination of a drill bit stem having a 90 socket extending upwardly from its lower end and a vertical bore extending from said socket upwardly throughout a considerable portion of said stem and communicating with the outside of the stem through a lateral bore, a drill bit having a shank with a threaded hub secured in said stem socket, said drill bit shank having a vertical bore leading therethrough from the upper end of said socket, means to deliver water from 95 said tank bore adjacent the cutting edge of the drill bit, and valve mechanism secured within said socket above the upper end of said hub, said valve serving to prevent the upward movement of the water through the 100 drill stem and comprising a pair of rigid plates having a central tubular projection, one of the projections extending into the other and constituting a valve seat, the other of said flanges being provided with a 105 transverse bridge spaced from the valve seat, a valve located between the valve seat and the bridge, and a spring acting upon the valve tending to maintain the valve seated against the valve seat.

3. In deep well drilling apparatus, the combination of a stem having means for delivering water downwardly therethrough, the lower end of the stem being provided with a socket, a drill bit detachably connected to said stem through a hub entering, said socket, said bit being provided with a central bore leading downwardly therethrough from said socket, and valve mechanism secured in said socket above the drill 115 120 125 130

bit hub, said mechanism including a pair of plates, one of the plates constituting a valve seat, a valve normally seated therein, resilient supporting means acting between 5 said valve and the other of said plates, and resilient means supporting the valve plates in position.

In testimony whereof I have signed my name to this specification in the presence of two subscribing witnesses.

CHARLES AUGUSTUS BUTLER.
